DESCRIPTION

U.S. PATENT DOCUMENTS

FIG. 1 is a perspective view of a knurled sleeve for co-axial cable connector in closed position showing my new design;
FIG. 2 is a side elevational view thereof all other sides, top and bottom plan views being identical thereto;
FIG. 3 is a nut view thereof; and,
FIG. 4 is a cable end view thereof.
The broken lines in the drawings depict environmental structure, which forms no part of the claimed design.
